UNITED STATES PATENT OFFICE.

JESSE A. B. SMITH, OF BROOKLYN, NEW YORK, ASSIGNOR TO UNDERWOOD TYPEWRITER
COMPANY, OF NEW YORK, N. Y., A CORPORATION OF DELAWARE.

CARBON-SHEET.

1.133.331.

Specification of Letters Patent. Patented Mar. 30, 1915.

Application filed December 10, 1914. Serial No. 876,409.

To all whom it may concern:

Be it known that I, JESSE A. B. SMITH, a citizen of the United States, residing in Brooklyn borough, in the county of Kings, city and State of New York, have invented certain new and useful Improvements in Carbon-Sheets, of which the following is a specification.

This invention relates to carbon sheets for use in a typewriting machine, such as made the subject of application No. 840,672, filed May 25, 1914, by Wernery and Smith. In operating said machine, several webs or work-sheets with intervening carbons are advanced at the same time, and after completion of the writing of a page, the pages are torn off, but the carbons are retracted, being drawn back between the webs into position for the writing of the fresh page. The carbon sheets are drawn back simultaneously by means of suitable mechanism, each carbon being attached to an arm. These arms are in the form of blades or bars which are arranged one behind another, in order to avoid undue separation of the plies of webs. It has been the custom, after attaching the rear edges of the carbon sheets to the successive arms or bars at the rear, to trim off the leading edges of the carbons, so that said edges register with one another.

The principal object of the present invention is to avoid loss of time and material in trimming off the carbon sheets, and to make it simple and easy to assemble the carbons in the machine, with their leading edges in alinement with one another.

To carry out this invention, I form each carbon sheet at its rear end with an extension of clear paper, that is, paper on which there is no coating of carbon, the extension being preferably integral with the carbon coated sheet; and this extension is provided with transverse lines or marks, at intervals corresponding to the spacing of the blade-like bars or arms of the typewriting machine. The extension may therefore be folded at the first line if the carbon is to be attached to the first arm, or at the second line if the carbon is to be attached to the second arm, to the third line if the carbon is to be attached to the third arm, and at the fourth line if the carbon is to be attached to the fourth arm, and so on; the lines being preferably marked accordingly, "1," "2," "3" and "4." When the sheets are folded upon

the respective arms in accordance with such marking upon the extensions, the leading edges of the carbon sheets will register with one another in the typewriting machine. By reason of the sheets being folded upon the arms, the latter are enabled to draw the carbon sheets backwardly between the plies of the webs; whereby each carbon may be used in writing a great number of pages.

In the accompanying drawing, Figure 1 is a perspective view of a part of a typewriting machine, showing the carbon-controlling arms and the carbon sheets with their extensions folded around the arms, the forward ends of the carbon sheets being in register, as shown in dotted lines. The work-sheets are shown as plaited or folded like a fan or an accordion, the carbons being inserted in the folds. Fig. 2 is a perspective view of a carbon sheet provided at the end opposite its leading end, with an extension having fold marks and numbers, to guide the operative in attaching the carbon sheets to the arms. Fig. 3 is a diagrammatic sectional side elevation of a portion of an Underwood front-strike typewriting machine of the kind shown in said application, to illustrate the general arrangement of the platen, work-sheets and carbons.

Types 1 strike against the front of a 85
platen 2, to make impressions on work-
sheets 3, between which are gathered carbon
sheets 4. The latter are attached to a recip-
rocating carriage 5, which is drawn for-
wardly by the platen as the sheets advance 90
around the same. The return of said car-
riage may be effected in any desired way.
The carriage slides to and fro upon a track
or frame 7. Detachably mounted upon the
carriage 5 are four blade-like bars or arms 95
8, to which the carbon sheets are attached
at their rear ends. The bars 8 are arranged
edge to edge in rear of one another, and
about on the same level. Each carbon sheet
is provided at its rear end with an extension
or tab 9, preferably of uncoated clear paper
and integral with the main sheet, and hav-
ing transverse lines or marks 10 thereon, to
indicate to the operator the various places
at which the tab may be folded, according
to the position of the arm to which the sheet
is to be attached; and the arms may be num-
bered to correspond with these lines on the
sheets, as seen at Fig. 1. The line on the tab
nearest to the carbon portion of the sheet is 110

numbered "1," which indicates that the tab is to be folded over the nearest of the bars 8. If the sheet is to be attached to the second bar, the tab will be folded at the line "2" 5 instead of at the line "1." The "2" line on the sheet is spaced from the "1" line by the distance between the rear edges of the bars. In the same manner, the sheet is to be folded at the "3" line if it is to be attached to the 10 third bar, or at the "4" line if it is to be attached to the rearmost bar of the set. By this means all of the leading edges of the carbon sheets are brought into proper alignment or register, without waste of carbon or 15 loss of time in trimming off the edges thereof. Each folded sheet may be held upon its bar by an ordinary paper-clip 11.

Variations may be resorted to within the scope of the invention, and portions of the 20 improvements may be used without others.

Having thus described my invention, I claim:

1. A carbon sheet having a leading end and an end opposite thereto, and having at 25 said opposite end an uncoated integral extension, said extension provided with a series of transverse fold-lines for the purpose specified.

2. A carbon sheet having a leading end and an end opposite thereto, and having at 30 said opposite end an uncoated integral extension, said extension provided with a series of transverse fold-lines for the purpose specified, said fold-lines being numbered.

3. A carbon sheet having a top end and a 35 bottom end, and having at said bottom end an uncoated extension provided with a series of spaced transverse fold-lines, for the purpose specified.

JESSE A. B. SMITH.
